UNITED STATES PATENT OFFICE.

MILTON M. SULGROVE, OF INDIANAPOLIS, INDIANA.

BREECHING-STAY FOR HARNESS.

SPECIFICATION forming part of Letters Patent No. 223,774, dated January 20, 1880.

Application filed October 6, 1879.

To all whom it may concern:

Be it known that I, MILTON M. SULGROVE, of Indianapolis, county of Marion, and State of Indiana, have invented a new and useful Improvement in Breeching-Stays for Harness, of which the following is a description, reference being had to the accompanying drawings.

The object of my invention is to provide a more durable, as well as a cheaper, breeching-stay than those heretofore in use, and one that shall, besides subserving the general purposes of a common leather breeching-stay, afford a loop or ring on which to hang or hold the back-straps.

My invention consists, mainly, in the new construction and arrangement of a metallic breeching-stay; also, in the combination of said stay with harness, all of which will be hereinafter first fully described in the specification, and then set forth in the claim.

In the accompanying drawings, in which like letters of reference in the different figures indicate like parts, Figure 1 represents a perspective view of one side only of the breeching, having my improved metallic stay attached thereto; and Fig. 2 is a side elevation of the stay detached from the breeching.

Referring now to the drawings, A A are the main bars of the stay, having a T-head or cross-bar, B, formed at one end, which is secured in the breeching by stitching the strap G' onto the strap G, over it, as shown in Fig. 1. The loop C is also formed at the other or front end of the main frame A A, into which the holdback-strap (not shown) is attached. To the straight side D of the loop C the breeching-strap G G' is secured, as shown.

The central upper part of the bars A A are provided with an upward extension part, in which is a slot, E, for the buckle-strap K to pass through, and a round bar, F, above the slot, around which the said buckle-strap is made fast, thus forming a means of securing the hip-strap L to the stay, as shown.

It is well known that the breaking loose of the breeching-stay from the breeching is a matter of frequent occurrence with the old leathern breeching-stay. By fastening the breeching-strap around the straight part D of the loop C and sewing the part G' of the breeching-strap to the part G, with the T-head B between them, as shown in Fig. 1, a strong and secure fastening of the supporting hip-strap to the breeching is secured, and at the same time a ring for the holdback-straps is obtained.

What I claim as new, and desire to secure by Letters Patent, is—

As an article of manufacture, a metallic breeching-stay consisting of the curved bars A A, having a T-head or cross-bar, B, formed at the outer end of one of the curved bars, a loop, C, formed at the outer end of the other curved bar, and the central part or union of the two curved bars provided with an upward extension, in which is a slot, E, as shown and described, for the purposes specified.

In testimony whereof I have signed my name to this specification in the presence of two subscribing witnesses.

MILTON M. SULGROVE.
